UNITED STATES PATENT OFFICE.

FRANK V. SIMONTON, OF ROSS, CALIFORNIA, ASSIGNOR TO THE REGENTS OF THE UNIVERSITY OF CALIFORNIA, A CORPORATION OF CALIFORNIA.

FILM HOLDER FOR DENTAL WORK.

Application filed January 19, 1926. Serial No. 82,213.

This invention relates to a holder whereby a film may be held and replaced in a predetermined position with relation to the teeth and X ray projector when making an exposure. In the treatment of pyorrhea and particularly in research work where a radiographic method of examination is conducted, it is very important to be able to determine accurately and to record the extent of destructive changes of the investing tissues previous to treatment, at intervals during treatment and at the conclusion of treatment. It is only upon the basis of such determinations and records that one is justified in drawing conclusions concerning improvements, continued destructive changes or the maintenance of status quo. This means that an operator must be able to positively control the several variables encountered. For instance, amperage, time of exposure of films, the type, strength, temperature, etc. of developer and time of development. Such variables are readily controlled with modern machines and are easily standardized, but there are other variables, namely, the relation of film, teeth and machine which have heretofore presented considerable difficulty. The invention forming the subject matter of the present application has overcome this difficulty. It consists in providing a film holder whereby predetermined relation of film, teeth and machine may be obtained with absolute accuracy thereby permitting roentgenographs to be reproduced under identical conditions from time to time as the treatment proceeds.

One form which this film holder may assume is exemplified in the accompanying drawings in which—

Fig. 1 is a side elevation of the film holder partly in section showing it in position within the mouth and positively adjusted with relation to the teeth and the compression cone on the machine.

Fig. 2 is a front elevation of the teeth of the patient showing the film holder in dotted lines and the bite plate in longitudinal section.

Fig. 3 is a plan view of Fig. 1 showing the film holder and bite plate removed.

Fig. 4 is a perspective view of the film holder.

Fig. 5 is a perspective view of the bite plate.

Referring to the drawings in detail, Fig.

1, A indicates the compression cone of an X ray machine, 2 the upper and 3 the lower teeth of the patient from which a radiograph record is to be made. B indicates in general the mouth piece or film holder placed in position within the mouth of the patient and C a graduated swivel head whereby the film holder is adjusted with relation to the teeth and the compression cone. The film holder proper consists of a plate 4 such as shown in Fig. 4, on the sides of which are formed flanges 5 to receive and secure the X ray film. Secured to the upper end of the plate is a cross bar 6 on which are formed two arms 7 and 8. The outer surfaces of the arms are provided with grooved guideways 9 to receive a bite plate generally indicated at 10 and the outer ends of the arms are provided with drilled openings 11 to receive pins 12 carried by a supporting arm 13. The bite plate is nothing more or less than a shallow tray having guide flanges 14 at opposite ends to be received by the guideways 9 of the arms 7 and 8 and side flanges 15 to receive and secure modeling compound such as shown at 16.

A film holder together with a bite plate forms a complete mechanism whereby a film may be supported with relation to the teeth or tissues to be radiographed, but accurate results cannot be obtained with these two devices alone as it would be impossible to secure a predetermined position with relation to the teeth and the machine. To secure such predetermined position the swivel head C has been provided. The swivel head carries a threaded pin 17 on which is turnably mounted an arm 18. This arm is carried by a bracket 19 secured to the compression cone and it is longitudinally adjustable in the bracket as shown and may be secured in any longitudinal adjusted position by means of a set screw 20. The outer end of the rod 18 is enlarged to form a head 21 which cooperates with the swivel head C. The threaded screw 17 passes through the heads C and 21 and a clamping nut 22 is employed to secure said heads when an adjusted position is assumed. Both heads are provided with graduations as indicated at 23 and a record may therefore be made of their related positions. The head C is provided with a perforated lug 24, this lug being provided for the reception of the arm 13. The arm is provided with a square shank 25 which extends

through the lug and the outer end of the shank is threaded to receive a clamping nut 26.

Arms 13 and 18 together with the swivel head C is the mechanism relied upon to obtain a predetermined position between the teeth, film and machine. In making an exposure with this device the procedure is as follows. A film is placed between the guide flanges 5 of the plate 4, a modeling compound softened by heating is placed in the tray 10 between the side flanges 15 and the tray is then placed on the arms 7 and 8 by passing the guide flanges 14 into the guideways 9. The film holder together with the tray and modeling compound in position is then placed in position in the mouth and in proper relation to the teeth so as to get an impression of several teeth. The compound is then chilled, which hardens it and fixes these imprints. The film holder and tray may now be removed and replaced at will. The compression cone is now focused, this being accomplished by loosening the nuts 20 and 22, loosening of nut 20 permits longitudinal adjustment and loosening of the nut 22 angular adjustment. When the proper focus is made with relation to the film holder, the nuts are tightened and an exposure is ready to be made. The tray carrying the modeling compound is replaced on the film holder and the entire device is again placed in the mouth of the patient. A roll of cotton wadding or the like such as indicated at 28 is placed on top of the arms 7 and 8. The patient is then instructed to bite down on the device as a whole to hold it securely in place. The pins 12 of arm 13 are then fitted into holes 11 of arms 9 of mouthpiece B, thus attaching the mouthpiece to the compression cone. The exposure may then be made and the device is removed by the patient opening the mouth widely and backing away from the film holder. A record is made of the longitudinal adjustment and the swivel head adjustment and the bite plate or tray 10 is retained for future use.

The tray 10 is made in quantity and a separate plate is used for each patient as it is obviously necessary to take radiographs from time to time as the treatment proceeds. When making the impression in the modeling compound when the first exposure is to be taken as few teeth are included in the impression as are essential to obtain stability and correct position, the reason being that the teeth are apt to move in the arches in the course of time and slight changes in position of a number of teeth might prevent the impression from going to place when a subsequent picture is taken. For instance, after an elapse of six months or a year.

Where it is desired to obtain fine detail of pockets formed in the tissue between the

teeth by pyorrhea, the same is accomplished by inserting a pin 30 into the pyorrhea pocket such as indicated at 31, the object being to ascertain any change in the exact depth of the pocket as subsequent radiographs are taken. A pin when inserted should also be held in a predetermined position with relation to the film and the machine and means are accordingly provided for obtaining such predetermined position. This is accomplished by providing a central opening 10^a in the tray, the modeling compound in register with this hole is cut out as indicated by the straight lines at 32. A small tube 33 is placed between the teeth and the pin 30 is inserted through the tube and into the pocket 31. Plaster of Paris or a like compound is then poured into the opening as indicated at 34 and permitted to set. The setting of the plaster of Paris determines not only the position of the tube 33 but also the pin, because if the pyorrhea pocket heals up or disappears the pin will project further up into the tube and each radiograph taken will show the place of healing.

After an exposure has been taken it is necessary to remove the bite plate and the film holder, this being accomplished by pulling the wire pin 30 back into the tube or completely out of the same to protect it from bending. In taking a second picture the film holder and bite plate are placed in position and as it carries the tube 33 the tube will be in direct position with relation to the pyorrhea pocket 31 and it is thus possible to readily reinsert the wire or pin 30.

The degree of accuracy possible with a device of this character has been well established as a number of double exposures have been made without any blur resulting.

While this device is primarily designed for use in pyorrhea it is equally applicable in all cases where it is desired to compare roentgenographs taken at different times of the same region. Such roentgenographs are only comparable when taken under conditions which permit control of all of the variables.

Having thus described my invention what I claim and desire to secure by Letters Patent is—

1. In a device of the character described, the combination with the compression cone of an X ray machine of a film holder adapted to be placed in the mouth of a patient rearwardly of the teeth to be radiographed, a bite plate carried by the film holder and adapted to receive and maintain the impression of a number of teeth to secure the film holder in a predetermined position with relation to the teeth, a tube adapted to be secured in a predetermined position in the bite plate so as to assume a predetermined position with relation to the teeth, a pin insertable through the tube and means whereby a pre-

determined position may be maintained between the compression cone, the teeth; the pin and the film holder.

2. In a device of the character described the combination with the compression cone of an X-ray machine of a bearing bracket secured to one side thereof, a rod longitudinally adjustable in said bearing bracket and extending forwardly from the cone at one side thereof, said rod terminating in a swivel bearing plate, a swivel head secured to the swivel bearing plate and turnable with relation thereto to assume different angles, means whereby the head may be secured against turning when a desired angle is secured, a bearing extension on the swivel head, a rod adapted to be detachably secured in said bearing and extending outwardly from the swivel head at substantially right angles thereto, and a combination bite plate and film holder adapted to be secured to said rod.
